United States Patent Office.

ANNIE W. HENDERSON, OF PITTSBURG, PENNSYLVANIA.

Design No. 3,515, dated June 1, 1869.

DESIGN FOR THE ORNAMENTATION OF GLASS-WARE.

The Schedule referred to in these Letters Patent and making part of the same.

To all whom it may concern:

Be it known that I, ANNIE W. HENDERSON, of Pittsburgh, in the county of Allegheny, and State of Pennsylvania, have invented a new and valuable Improvement in a Design for the Ornamentation of Glass-Ware; and I do hereby declare that the following is a full, clear, and exact description of the same, reference being had to the annexed drawings, making a part of this specification.

What I claim as my invention, and desire to secure by Letters Patent, is—

The design for ornamentation of glass-ware herein described and shown.

In testimony that I claim the above, I have hereunto subscribed my name in the presence of two witnesses.

ANNIE W. HENDERSON.
